UNITED STATES PATENT OFFICE.

SIGMUND JOSEPH PENTLER AND OTTO R. SHORT, OF WAUSAU, WISCONSIN.

UPPER TURNER.

Application filed November 17, 1921. Serial No. 515,767.

To all whom it may concern:

Be it known that we, SIGMUND JOSEPH PENTLER and OTTO R. SHORT, both citizens of the United States, and residents of Wausau, in the county of Marathon and State of Wisconsin, have invented certain new and useful Improvements in Upper Turners; and we do hereby declare that the following is a full, clear, and exact description thereof.

10 Our invention is a device for turning up the uppers of shoes to facilitate the affixation of the welt and outsole.

It is especially adapted for stitching down shoes and designed to operate on a shoe after it is lasted and inseamed.

15 It is provided with anvil and hammer portions functioning to apply pressure to pull the upper upward and outward from the shoe, flattening out the edge and giving it 20 the right shape; to press the inseam stitch down, to better enable the welting to cover same; to straighten the inseam stitch to form a uniform line at the extreme bottom edge of the insole and to shape the upper 25 into a flange for the attachment of outsole.

An important feature of the invention is the construction of the hammer whereby it will adjust itself to different dimensions of different leather.

30 Other objects will appear as the description proceeds.

Reference is had to the accompanying drawings, in which—

Figure 1 shows a side elevation with parts 35 in section.

Figure 2 shows a plan of the same.

Figure 3 shows a vertical cross section through the shaft.

Figure 4 shows a detail of the anvil and 40 hammer.

The same reference characters are used throughout the figures to indicate the same parts.

Integral with base 10 are standards 45 11 and 12 provided with bushings 13 and 14 respectively, in which is positioned a rotatable shaft 15 having slot and key relationship with clutch 16, provided with a suitable handle 17 for throwing in and out of engagement with sheave 18, on which a belt 50 is adapted to operate, and which is rotatable upon shaft 15.

Spring actuated pin 19 is provided to coact with pin 20 to retain the clutch in or 55 out of engagement.

Rigid with shaft 15 is fly-wheel 21, pro-

vided with an eccentric pin 22 on which pitman 23 provided with a suitable bearing surface, is attached to rotate. Also integral with base 10 is standard 24 hollowed out 60 at 25 and provided with a transverse shaft 26 on which lever 27 is mounted for rotation.

Lever 27 is provided with lugs 28 apertured to receive a pin 29, affording pivotal 65 relationship of lever 27 with pitman 23, lever 27 being provided with chamber 30 for the reception of the pitman. Lever 27 is also provided with lugs 31 receiving transverse pin 32 on which hammer 33 is 70 pivoted and prevented from outward movement by plate 34. Spring 35 tends to hold hammer 33 in an outer position and is affixed at 36 to lug 37 on lever 27. Standard 24 is provided with grip 38, having horizontally directed screws 39 for regulating the horizontal position of anvil 40 and screws 41 for regulating the vertical position of said anvil, the screws being adjustable by reason of their threaded relationship. 75 80

In the operation of the device, power is transmitted to shaft 15 through sheave 18 when the clutch is thrown in, thus rotating fly-wheel 21 and pin 22, and moving pitman 85 23. This causes lever 27 to move up and down causing hammer 33 and anvil 40 to contact.

When a shoe is subjected to the operation of the machine, the upper 44 has been provided with an inseam, last 42 being shown in Figure 4 between the insole 43 and the upper. 90

As shown in Figure 4, anvil 40 provides a rest and guide for the shoe which is moved 95 along the extreme end thereof. Hammer 33 in its upward movement presses down the inseam stitch and straightens it to form a uniform line at the extreme bottom edge of the insole and turns the upper outward 100 flattening it and shaping it into a flange for the attachment of the outsole and the reception of the welting on its upper surface. Hammer 33 moves into the position shown in dotted lines in Figure 4, thus exerting a 105 pulley action.

It is apparent that the inclined surface and the pivotal action of hammer 33 adapt it to operate on different dimensions of upper leather. 110

We claim:

1. In an upper turner, an anvil provided

with a downwardly directed portion, having a flat inclined face, and a hammer having a corresponding plane face and movable to press an upper against said anvil, said inclined faces being directed at an acute angle with respect to the line of travel of said hammer.

2. The method of treating a lasted and in-seamed shoe, comprising flattening and drawing upward and outward by stretching pull of a small area of the upper projecting beyond the inseam stitch and pressing down and straightening the inseam stitch on the border of said area, said flattening, drawing, pressing, and straightening being performed substantially simultaneously; and the simultaneous flattening, drawing, pressing, and straightening of succeeding areas to shape and prepare the upper for attachment of the out sole.

3. In an upper turner, an anvil support therefor a lever pivoted to said support, a hammer pivoted thereto, a spring for directing said hammer outwardly, said hammer and said anvil having correspondingly inclined surfaces for gripping and pulling the shoe upper, and means for reciprocating said lever.

4. In an upper turner, an anvil, a support therefor, means for adjusting the position of said anvil on said support, a lever pivoted to said support, a hammer pivoted thereto, a spring for directing said hammer outwardly, said hammer and said anvil having correspondingly inclined surfaces for gripping and pulling a shoe upper and means for moving said lever up and down.

5. In an upper turner, an anvil, a support therefor, means for adjusting the position of said anvil on said support and securing said anvil immovable in adjusted position, a lever pivoted to said support, a hammer pivoted thereto, a spring for directing said hammer outwardly, said hammer and said anvil having correspondingly inclined surfaces for gripping and pulling a shoe upper, and means for reciprocating said lever.

6. The combination of a reciprocating member, a pivot thereon, a hammer on said pivot having a flat contact face inclined with respect to a line passing from said pivot to said face, and an anvil having a contact face inclined to cooperate with said hammer, said pivot and said contact faces being always substantially alined.

7. In an upper turner, an anvil, a support therefor, means for adjusting the position of said anvil on said support, a lever pivoted to said support, means for reciprocating said lever, a hammer pivoted on said lever and reciprocated thereby, said anvil and said hammer having contact faces inclined with respect to the line of travel of said hammer, said hammer being adapted to contact with a shoe upper on said anvil, and resilient means urging the inclined face of said hammer towards the inclined face of said anvil, but yielding as said faces approach, said hammer face sliding as said hammer moves upwardly to exert a pulling action on said shoe upper.

8. The combination of a support, a lever pivoted thereto, a hammer pivoted to said lever and having a face inclined with respect to a line running from the pivotal point to said face, an anvil secured to said support adapted to contact with a shoe upper and having a face inclined to cooperate with the face of said hammer but of larger dimensions than that of said hammer, means for moving said lever to cause said hammer to contact with said shoe upper, the ends of said faces adjacent the shoe being directly opposite each other, and resilient means for directing said hammer outwardly to permit inward movement thereof, and a sliding inwardly of the face of the hammer with respect to the face of the anvil.

In testimony that we claim the foregoing we have hereunto set our hands at Wausau, in the county of Marathon and State of Wisconsin.

SIGMUND JOSEPH PENTLER.
OTTO R. SHORT.
